MECHANICAL MOVEMENT

Edward H. Korte, Brooklyn, N. Y.

Application February 7, 1945, Serial No. 576,585

7 Claims. (Cl. 46—1)

1

This invention relates to a mechanical movement in general, and more particularly to a toy involving a new mechanical movement.

Among the objects of the present invention, it is aimed to provide an improved mechanical movement for transmitting motion to an object, and more particularly to cause an object to move away from a particular point.

It is still another object of the present invention to provide an improved toy including a novel mechanical movement for transmitting motion to an object, and more particularly to cause an object to move away from a particular point.

It is still another object of the present invention to provide an improved toy including a novel mechanical movement for transmitting motion to an object, and more particularly to cause an object to move toward or from a particular point.

These and other features, capabilities and advantages of the invention will appear from the subjoined detail description of specific embodiments thereof illustrated in the accompanying drawing in which

Fig. 1 is a plan view partly in section of one embodiment.

Fig. 2 is a side elevation partly in section of the embodiment shown in Fig. 1.

Fig. 3 is a perspective on a smaller scale of another embodiment.

Fig. 4 is a side elevation of the embodiment illustrated in Fig. 3.

In the embodiment shown in Fig. 1, there is illustrated a movable device such as the main body, block or weight 1 shown as rectangular with eyelets 2 and 3 extending from the sides 4 and 5 of the block adjacent the rear end of the same, control reins 6 and 7 composed of ordinary twine, cord, or the like, preferably at least three feet in length. The two reins 6 and 7 may be parts of a single loop, as shown, and in some instances composed of ordinary No. 60 sewing thread.

Adjacent the front end 8 of the block 1, and extending from the bottom 9 thereof, there are provided a plurality of sharp pointed projections, prongs or pins 10 and 11, two being shown in the present instance. These pins 10 and 11 preferably each have an enlarged body portion 12 and diminished extension 13 terminating in a sharp point 14 as shown in Fig. 1.

The two picks or pins 10 and 11 incline rearwardly as shown in Fig. 1.

Excellent results have been achieved when the angle between the pins 10 and 11 and the bot-

2

tom 9 of the block is approximately 45°; when the pins 10 and 11 are similar in construction to that of phonograph needles; when the body 1 is composed of wood about two and one-half inches wide from side 4 to side 5, about one and three-quarters inches from front to rear, and about three-quarters of an inch from top to bottom; and when the eyelets are positioned about one-eighth inch from the bottom 9, and about one-quarter inch from the front end of the block 1.

In operation the block 1 is placed on a supporting surface, preferably having a nap such as the nap of a rug or a textile surface, such as a table cloth if the table cloth is provided with the well-known table pad beneath the table cloth. The attendant or operator then places the block 1 on a supporting surface when the pins 10 and 11 will partially penetrate the supporting surface. Thereupon with the reins 6 and 7 extending forwardly of the front end of the block 1, the attendant will first pull on one rein and then on the other, and the block 1 will start moving away from the attendant or operator. This action results from the fact that when the rein 25 6 is drawn rearwardly, the pin 11 will move forwardly with the block describing an arc around the pin 10 as a fulcrum, and in turn when the rein 7 is then drawn rearwardly while the rein 6 is slack, the block will turn about the pin 11 as a fulcrum and cause the pin 10 to move forwardly describing an arc around the pin 11. With this toy any number of games can be played, as an instance, a competitive game in which several blocks are operated by different players to see which player is most skillful and can cause his block to arrive at a certain predetermined destination ahead of the others.

In the embodiment shown in Fig. 3, instead of the block 1, a body 15 is shown having two cross pieces 16 and 17, the cross piece 16 preferably being longer than the cross piece 17, which cross pieces 16 and 17 have mounted on the same weight 18 which extends a short distance beyond the front end of the cross piece 16. The ends of the cross piece 16 are connected to the ends of the reins 19 and 20 which are preferably three feet in length and which may be part of a single loop. To each side of the weight 18 the cross piece 16 is provided with a surface engaging pin, to wit, the pins 21 and 22. As shown in Fig. 4, the pins 21 and 22 extend below the lower face of the cross piece 16 inclining rearwardly and forming an angle approximating 45° with the lower face of the cross piece 16. Excellent results have been achieved when the pin ex-

tensions 21 and 22 below the lower face of the cross piece 16 do not exceed one-eighth of an inch in length.

Excellent results have been achieved with this second embodiment when the cross piece 16 approximates ten inches in length, the cross piece 17 approximates six inches in length, and the weight 18 approximates two ounces in weight.

In operation the body 15 is placed on a textile surface preferably, such as a rug, with the pins 21 and 22 partially penetrating and extending into the rug. In use, the attendant will alternately pull on the reins 19 and 20 when the pins 21 and 22 will cause the body 15 to move away from the player if the front end of the body 15 is positioned so that its cross piece 17 faces the player. To add interest to the game, the body 15 can also be manipulated by the reins 19 and 20 to move toward the player. If the body 15 is moving away from the player in the position shown in Fig. 3, it will only be necessary for the player to pull either the rein 19 or the rein 20 a sufficient distance so that the reins can be switched from one hand to the other and the body 15 turned around so that the front end then faces the player. The continued alternate actuation of the reins 19 and 20 will then cause the body 15 to move toward the player. In turn, in order to reverse the direction of the body 15, it will again only be necessary for the player to exercise a sufficient pull on either the rein 19 or 20 to turn the body 15 around again and then inter-change the reins and again alternately actuate the same, again to cause the body 15 to move away from the player.

Instead of the reins 6, 7 and the reins 19, 20, any other suitable control can be used for alternately causing the block 1 or the block 15 to move from side to side. Obviously rigid rods pivotally connected to the sides of the block in place of the reins 6, 7, and in turn rigid rods pivotally connected to the ends of the cross piece 16 in place of the reins 19, 20, might serve in order to exercise alternate pulling forces on either the body 1 or the body 15 to cause same to move from side to side.

In certain cases, as an instance, where the supporting surface presents a deeper nap than is the case with other surfaces, it may be desirable to cause the needles 10, 11 in the present instance frictionally held in position to be caused to extend farther from the lower face of the block 1 or cross piece 16 than as shown in Fig. 2. With the needles 10, 11, the enlarged portions 12 would then protrude from the lower face 9 and form a limiting stop for the extent that the needles will penetrate or project through the nap into the rug weave. In turn, when used on a surface, such as a table cloth without a nap, to insure effective and smooth operation, the enlargements 12 will prevent excessive penetration of the needles 10 and 11.

Furthermore, abutments for the ends of the reins 6 and 7, such as the eyelets 2 and 3, may be spaced from the sides 4 and 5, more particularly disposed a greater distance laterally from the needles 10 and 11 to increase the leverage transmitted to the block 1 by the rein 6, 7 being pulled and thereby effect a smoother operation.

It is obvious that various changes and modifications may be made to the details of construction without departing from the general spirit of the invention as set forth in the appended claims.

I claim:

1. The combination of a body, a pair of prongs

or pins extending from the lower face thereof to engage a supporting surface, said pins inclining rearwardly, and a pair of control means connected to the body removed from said pins to facilitate alternately exercising a pulling force on said control means in turn to cause the body to move from side to side.

2. The combination of a body, a pair of prongs or pins extending from the lower face thereof to engage a supporting surface, said pins inclining rearwardly, being spaced from one another and positioned near the front end of said body, and a pair of control means connected to said body and spaced laterally from said pins to enable moving the body from side to side when exercising alternate pulling forces on said control means, causing the body at one time to rotate about one pin as a fulcrum and at another time to rotate in the opposite direction around the other pin as a fulcrum.

3. The combination of a body, a pair of prongs or pins extending from the lower face thereof to engage a supporting surface, said pins being spaced from one another inclining rearwardly and being disposed at the front end of said body, said pins having an enlarged body portion with a diminished portion about one-eighth of an inch in length terminating in a sharp point, and a pair of control means connected to said body, said control means being spaced laterally from said pins to enable pulling forces alternately on said control means to cause the body to rotate first about one pin as a fulcrum and then about the other pin as a fulcrum.

4. The combination of a body, a pair of prongs or pins extending from the lower face thereof to engage a supporting surface, said pins inclining rearwardly being spaced from one another and disposed at the front end of said body, eyelets secured to the sides of said body adjacent the rear end thereof, said eyelets being spaced laterally from said pins, and flexible control reins secured to said eyelets to enable said body to be rocked from side to side by alternately exercising pulling forces on said reins, alternately to rotate about one pin and then about the other pin.

5. The combination of a body having an elongated cross piece at the front end and a shorter cross piece to the rear of said elongated cross piece, a pair of prongs or pins extending from the lower face of said elongated cross piece, one prong to either side of said body to engage a supporting surface, said pins inclining rearwardly and disposed adjacent the front end of said elongated cross piece, and a pair of control reins each connected to one end of said elongated cross piece spaced from said pins to facilitate rocking said body about one pin or the other as vertical axes to cause said body to move in one direction or to reverse the direction of movement of said body to facilitate moving said body in the opposite direction.

6. The combination of a body, a pair of prongs or pins extending from the lower face thereof to engage a supporting surface, said pins being spaced from one another inclining rearwardly and being adjustably mounted at the front end of said body, said pins having an enlarged body portion with a diminished portion terminating in a sharp point, and a pair of control means connected to said body, said control means being spaced laterally from said pins to enable pulling forces alternately on said control means to cause the body to rotate first about one pin as a fulcrum and then about the other pin as a fulcrum,

said pins being adjustably mounted in said body to afford a greater or less projection of said enlarged portions depending upon the character of the supporting surface.

7. The combination of a movable device, a plurality of prongs or pins associated with such movable device, said pins inclining rearwardly, and a pair of control means connected to the mov-

able device removed from said pins to facilitate alternately and successively exercising a pulling force on one control means and then on the other control means in turn to cause one part and then the other part of the removable device to move forwardly.

EDWARD H. KORTE.
